SAMUEL SECKENDORF, OF NEW YORK, N. Y., ASSIGNOR TO JOHNSTON & SECKENDORF,
OF NEW YORK, N. Y., A COPARTNERSHIP.

RELEASING MECHANISM.

1,297,019.

Specification of Letters Patent. Patented Mar. 11, 1919.

Application filed May 10, 1917. Serial No. 167,672.

To all whom it may concern:

Be it known that I, SAMUEL SECKENDORF, a citizen of the United States, residing at New York, in the county and State of New York, have invented certain new and useful Improvements in Releasing Mechanism, of which the following is a full, clear, and exact description.

The invention which constitutes the subject matter of this application relates to a lorgnette or eye-glass, the construction, objects, operation and advantages of which will appear from the detailed description below.

15 In the drawings:

Figure 1 is a rear view of the lorgnette in open position, that is its position for use.

Fig. 2 is a rear view illustrating the device in completely closed position suspended 20 from its cord or chain.

Fig. 3 is a longitudinal section taken centrally through Fig. 2 but looking in a direction at right angles to the view in Fig. 2.

Fig. 4 is an enlarged detail illustrating the 25 novel means for maintaining or holding the lorgnette in folded position.

Fig. 5 is a detail view illustrating the resilient connection between the two bridge portions connecting the glass settings or 30 frames.

Referring to the drawings in detail the reference numeral 10 designates a sheath or mounting preferably of rectangular construction, provided with an outer flange or 35 gallery 11 and a stem or neck portion 12, the end of which is connected to a cord or chain 13 from which the lorgnette is normally suspended. The mounting is adapted to receive the frames 14 and 15 of the glasses. 40 These frames are provided with bridge portions 16 and 17, respectively, pivoted to each other at 18. The frame 14 is pivoted at 19 to the mounting 10.

In folding the lorgnette the frame 15, as 45 viewed from Fig. 1, is rotated in a folding direction about its pivotal point 18 as a center until it comes into contact with and lies flat upon frame 14. The two frames or settings are now moved or folded bodily in a 50 direction about the pivot 19 as a center until they lie flat upon the bottom of the mounting 10, in which condition the frames 14

and 15 will be within the borders of the gallery 11.

The axes of the pivots 18 and 19 are located substantially in the same plane. This not only enables the setting or frame 15 to be positioned between the setting 14 and the sheath 11, but also enables the successive folding movements to take place in planes 60 extending in the same general directions.

The chain 13 is connected to the stem or neck 12 through the ring 21, spring pressed plunger 22 and casing 23, in which said plunger is located, said casing being rigidly 65 mounted in said neck 12. The plunger 22 is provided with a shouldered portion, or piston 24 adjacent to lower end which snugly fits the cylindrical casing 23 and in which it has a limited reciprocating movement. To 70 the shouldered portion 24 is preferably attached a plurality of fins 25 adapted to slide in slots 26 in the casing 23. These fins and slots not only serve to limit the upward movement of the plunger 22, but also prevent any rotary movement being imparted thereto. The plunger head 27, to which the ring 21 is attached, limits the downward movement of the plunger 22. The plunger 75 also carries a member 28 which in the folding operation snaps into a notch 29 contained in the end of the bridge portion 16, the latter being rounded or cam-edged in order to cam the plunger 22 outwardly 80 against the tension of a spring 30, located 85 between the upper end of the casing 23 and the shoulder 24.

So long as the member 28 is in effective engagement with the notch 29 the lorgnette is securely held in folded position. If now 90 it is desired to use the lorgnette a pull is exerted upon the chain 13 which retrieves the plunger 22, disengaging the member 28 from the notch 29 when the frames will spring out to their correct optical positions 95 about their respective pivots as previously described. The frame 15, in folded position, locates itself between the frame 14 and the bottom of the sheath 10. When the member 28 is therefore disengaged from notch 29 100 the spring 31 surrounding the pivot pin 32 is strong enough to initiate the movement of the frames 14 and 15 to open position. From the foregoing it will be seen that in

the operation of folding the lorgnette or other spectacle the bridge portion is automatically engaged by the spring-pressed plunger which locks the same in folded position and that when it is desired to use the lorgnette it is only necessary to exert a slight pull upon the chain 13. This chain is invariably anchored and to use the lorgnette it is only necessary to grasp the sheath 10 and exert a slight pull thereon which disengages the member 28 from the notch 29 and the parts then open automatically under the tension of the spring 31. For all practical purposes therefore the device may be manipulated to open position by one hand.

It will of course be understood that the bridge portions 16 and 17 are provided with coöperating shoulders which limit the opening movement of the same, such as that employed in connection with an ordinary hinge; it will also be understood that the frames 14 and 15, bridge portions 16 and 17, mounting 10 and shank 12 may be made of any desired material; and it will be further understood that many changes may be made in point of detail and other embodiments resorted to without necessarily deviating from the true spirit and scope of my invention.

30 What I claim is:

1. A folding lorgnette or other spectacle, comprising a sheath, a spring pressed plunger mounted in said sheath, eye-glass settings adapted to fold into said sheath, and coöperating means on the settings and said plunger for automatically interlocking said sheath and settings in folded relation.

2. A folding lorgnette or other spectacle, comprising a sheath and foldable settings 40 pivotally connected to said sheath, and provided with a notch therein, in combination with a spring-pressed plunger mounted upon said sheath adapted to snap into said notch in the folding operation of the lorgnette.

45 3. A lorgnette or other spectacle, comprising a sheath, a plunger mounted in one end of said sheath, a glass setting pivoted to said sheath, a second setting pivotally connected to the first mentioned setting and 50 adapted to be positioned between the sheath and said first mentioned setting, and coöperating means on said first mentioned setting and plunger for automatically effecting a snapping engagement in the folding operation of the lorgnette.

55 4. A lorgnette, comprising settings foldable upon each other and provided with a notch at the pivotal point, a sheath to which said settings are pivoted and in which they 60 are adapted to be inclosed, and a supporting plunger mounted upon said sheath and adapted to snap automatically into said notch when the settings are being folded into said sheath.

65 5. A lorgnette, comprising settings fold-

able upon each other, a sheath to which said settings are pivoted and into which they may be folded and a supporting spring-pressed plunger provided with means coöoperating with said settings for automatically interlocking said settings in said sheath by the folding operation of the lorgnette.

6. A lorgnette, comprising foldable settings, a sheath into which said settings may be folded, a spring-pressed plunger mounted in said sheath, a supporting cord attached to one end of said plunger and the other end of said plunger adapted to effect a snapping engagement with said settings, whereby the settings are automatically locked by 70 the folding of same and released by exerting a pull upon said cord.

7. A lorgnette comprising settings relatively foldable upon each other, a handle member to which one of said settings is connected, a resilient locking device carried by said member, a supporting cord attached to one end of said device and the other end of said device adapted to effect a snapping engagement with one of said settings, whereby the settings are automatically locked by 80 the folding of the same and released by exerting a pull upon the supporting cord.

8. A lorgnette comprising settings relatively foldable upon each other, a handle 90 member to which one of said settings is connected, a casing mounted upon said member, a spring pressed locking plunger carried by said casing, and a supporting cord attached to one end of said plunger and the other end of said plunger adapted to effect a snapping engagement with one of said settings, whereby the settings are automatically locked by 100 the folding of the same and released by exerting a pull upon the supporting cord.

9. A lorgnette comprising settings pivotally connected to and adapted to fold upon each other, a sheath to which one of said settings is pivoted, the axis of the said pivots lying substantially in the same plane, a locking device mounted in said sheath, a supporting cord attached to one end of said device and the other end of said device adapted to effect a snapping engagement with one of said settings, whereby the settings are automatically locked by 110 the folding of the same and released by exerting a pull upon the supporting cord.

10. A lorgnette comprising a setting, a second setting pivotally connected to and 120 adapted to be folded upon the first mentioned setting, a sheath to which the first mentioned setting is pivoted, and into which the settings are adapted to be folded, the said pivots lying substantially in the same 125 plane, whereby the second mentioned setting in the folded position of the lorgnette is located between the first mentioned setting and the sheath.

11. A lorgnette comprising a setting, a 130

second setting pivotally connected to and adapted to be folded upon the first mentioned setting, a sheath to which the first mentioned setting is pivoted and into which 5 the settings are adapted to be folded, the said pivots lying substantially in the same

plane, whereby in the folding movements the settings define planes which extend in substantially the same direction.

In testimony whereof I hereunto affix my 10 signature.

SAML. SECKENDORF.
